UNITED STATES PATENT OFFICE.

JASPER LUCIUS CATLETT, OF VINCENNES, INDIANA.

SYSTEM FOR NUMBERING MOTOR-CARS.

1,346,808.

Specification of Letters Patent. Patented July 20, 1920.

Application filed July 22, 1919. Serial No. 312,507.

To all whom it may concern:

Be it known that I, JASPER L. CATLETT, a citizen of the United States, and a resident of Vincennes, in the county of Knox and State of Indiana, have invented certain new and useful Improvements in Systems for Numbering Motor-Cars, of which the following is a specification.

My invention is an improvement in systems of numbering motor cars, and has for its object to provide a simple method of numbering and tagging such vehicles, so arranged that the vehicle may be guarded against theft and the State against loss of fees, wherein a permanent number is provided for each car, and a removable record of the said number for each car, the removable records being arranged in sets, distinguished from each other in any preferred manner to provide for different years.

In the drawings:

Figure 1 is a side view of a motor car provided with the improved system of numbering;

Fig. 2 is a plan view of the removable plate holder;

Fig. 3 is a section on the line 3—3 of Fig. 2;

Fig. 4 is a view similar to Fig. 2, showing a modified arrangement of plate;

Fig. 5 is a diagrammatic view showing the method of indicating numbering by openings;

Fig. 6 is a similar view showing the manner of indicating the numerals by openings.

In the embodiment of the invention shown in Figs. 1, 2 and 3, a pair of plates 1 is provided for each car 2, the said plates being arranged at any desired point on the car, as, for instance, on the door 3, and a suitable holder 4 is provided for the plate. This holder is a pocket, having its outer side cut away over the greater portion of its extent to expose the plate 1 to view, and the plate carries suitable identifying matter, as, for instance, a number indicated at 5, which is the number of the car, another number indicated at 6 which is the year in which the plate is used, and a legend 7 indicating the State, in the present instance "Ind.", for Indiana.

The holder is held to the car in any suitable manner, as, for instance, by the screws 8, and on the car, in the present instance just below the holder, there is painted on the door data indicated at 9, corresponding to

that on the plate, namely, the number of the car and the State abbreviation and the year. This number is painted on the car in any suitable or desired manner, but in such manner as to make an imperishable record, and the plates are removable from the holder, that is, they may be lifted out easily from the holder so that the owner of the car may take them with him when he leaves the car.

In use, the numbers on the car are never changed. That number which is given the car when it is first registered is carried by the car throughout the life of the car or throughout its use in the State in question. This number is registered in the archives of the State, and the owner of the car will be called upon to pay the required fees every year.

In order to easily keep track of these fees and their payment, two sets of plates may be used, differently colored, one set being used in odd and the other in even number years. In the even years, 1918 and 1920, a set of plates might be used having white backgrounds and black figures, and in the odd years, 1919 and 1921, for instance, a set could be provided having blue backgrounds and white figures, or any other desired combination.

A car bought in 1918, for instance, would have its number assigned and with the color of the year. In 1919 the owner of the car would surrender the plate to the State and receive a new plate bearing the same number, but properly colored for that year. These two sets of plates would be all that the State would be required to furnish, and the plates could be continued in use so long as the car was in use. Every year the owner would surrender one set of plates and obtain the other set.

On leaving the car for any purpose, the owner of the car will remove the plates from the holders, dropping them in his pocket and replacing them when he returns. When the car is traveling without the plates it will be evident at a glance that there is something wrong, and an investigation will be brought about in this manner. With the years designated by number it is obvious that a new set of plates would be necessary every year.

If the different classes of cars are separately registered, as, for instance, trucks and the like, different colored plates may be used in the same manner. When the car

is worn out the plates should be returned to the State for credit, since they are never sold to the car owner. This system reduces the number of figures used in the numbering of the car, since on the first of each year the State has only to issue numbers for the new cars or for those cars which have come into the State during the year.

It will be understood that in practice the 10 number plates 1 will be of steel, with the enameled numbers baked thereon. These plates will be furnished by the State and since the enameled plates must be made by establishments making a specialty of such 15 work, they cannot be easily counterfeited. It will be evident that when the numbers are indicated by the openings as shown in Figs. 4 and 6, these openings may be placed at any point on the car. As shown, they are directly beneath the plate 1, that is, at the 20 holder. It is obvious, however, that they may be anywhere else, and the openings are a part of the car, being of the material of the car itself.

25 In Figs. 5 and 6 it will be noted that the starting point at the left is a single drill hole, approximately six-thirty-seconds of an inch, and a little larger than those which indicate the numbers, and this opening 11 is 30 below the line. The period is provided for by an opening 12 of the same size and it, like the opening 11, is placed below the line. The same size opening is used for the naught 13, but the said opening is above the line, 35 the line being a horizontal line of any convenient length, placed at the point where the openings are to be made. Those openings representing the numbers 1, 2, 3, 4, 5, 6, 7, 8 and 9 are placed in vertical alignment above 40 this line and each vertical series is provided with a like opening indicated at 14 at the left and at the level of the topmost opening of the series. It will be evident that any opening drilled above this would immediately 45 indicate that the said opening did not belong in the series, and that the arrangement had been tampered with. This drilling system is used in connection with the enameled plates and the gold-figures on the 50 side of the car, if desired, instead of numerals and letters, and the number of the car, the year and the State may be indicated by the numbering system shown in Fig. 4. In this arrangement the numerals are indicated 55 by the number of perforations in the vertical lines, as, for instance, the numerals indicating the number of the car and the year are formed by vertical rows of perforations, the number of perforations in the rows indicating the numeral. As shown, the car 60 number is 226677, the year 8, and the State is represented by number also, 6 in the present instance. At the left of each vertical row of perforations there is provided a lock 65 perforation, the said lock perforation being

level with the highest numeral indicating perforation so that the addition of another perforation will be immediately noticed. The large size openings below the vertical rows of openings indicate periods.

In Fig. 6 is shown the method of using the perforations. It will be noticed that one perforation indicates "1," two in a vertical row, "2," three in a vertical row, "3" and so on. At the top and at the left hand 70 of each series there is an opening 14 which is the lock to prevent addition of other numerals or to prevent changes in the arrangement. It will be obvious that should, for instance, a perforation be added above the 80 lock perforation, such additional perforation will be immediately noticed and will be evidence that the arrangement has been tampered with.

I claim:

1. A system of numbering motor cars which consists in providing the car with a number permanently fixed thereon and forming a permanent record and with a number removable therefrom and adapted to be 90 removed when the owner leaves the car, for the purpose specified, said removable numbers being on plates having data for indicating the year and State.

2. A system of numbering motor cars 95 which consists in providing the car with a number permanently fixed thereon and forming a permanent record and with a number removable therefrom and adapted to be removed when the owner leaves the car, for the 100 purpose specified.

3. A system of identifying and numbering motor cars, which consists in placing on the car permanent identifying data to form a permanent record on the car, and in providing similar data on a plate removable from the car and normally mounted thereon.

4. A system of identifying and numbering motor cars which consists in placing on the car permanent identifying data to use 110 throughout the life of the car, and in providing similar data removably attached to the car to be removed therefrom when desired.

5. The combination with a motor car, of a 115 set of identifying data permanently fixed thereto and forming a permanent record, and a similar set removably connected therewith.

6. A system of identifying and numbering motor cars which consists in placing on the 120 car a permanent record of the number, each numeral of the series composing the car number being indicated by a series of vertically arranged openings, and a lock opening at one side of each series at the topmost opening thereof for this purpose.

7. A system of identifying and numbering articles, which consists in placing on the article a permanent record in the form of a number, the numerals composing the num- 125 130

ber being indicated by series of openings, the openings of each series starting from a horizontal level, and each series having a lock number arranged at the side of the topmost opening.

8. A method of numbering articles, which consists in substituting series of perforations for the numerals, said perforations of the series being arranged one above the other 10 and in providing a lock perforation at one side of the topmost perforation of the series.

9. A system of identifying and numbering articles, which consists in providing in the article series of perforations, the perforations of each series indicating a number and 15

having a laterally arranged perforation at the top to prevent the addition of other perforations to change the numbering and in providing removable plates bearing the same indications in numerals.

10. In combination with an article of manufacture, of identifying data permanently made a part of such article and plates carrying the same identifying data connected with the article in such manner that they may be easily and quickly removed therefrom or attached thereto to permit them to be carried in the pocket of the owner when the article is out of his immediate possession.

JASPER LUCIUS CATLETT.
